UNITED STATES PATENT OFFICE

2,337,712

SOFA BED

Martin Fox, Chicago, Ill., assignor to The Seng
Company, a corporation of Illinois

Application September 12, 1942, Serial No. 458,100

2 Claims. (Cl. 5—47)

This invention relates to sofa beds, and more particularly to the type in which two sections forming a seat portion and a back portion are hingedly connected together and movably mounted on a supporting frame by means of pitmans so that the device may readily be converted to either a sofa or bed.

The primary object of the invention is to provide an attractive, easily operable structure which is thoroughly reliable in operation but can be constructed with a minimum of strategic materials, such as iron and steel. The present structure has its parts so designed that most of the mechanism may be made of wood.

Another object of the invention is to provide a convertible sofa wherein the back section and seat section are hinged together and provided with an automatically engageable latch which serves to hold the two sections in proper angular relation when either of the sections is moved from the horizontal bed position to proper angular relation to form a sofa. As both of the sections and the latch are movable as a unit on the pitmans, it is very convenient to tilt the seat section upwardly so that the latch is readily accessible for release by the operator's hand or foot.

The invention is illustrated in a preferred embodiment, in the accompanying drawings, in which—

Figure 1 is a side elevational view illustrating the preferred embodiment of the invention with the mechanism arranged to form a sofa; Figure 2, a sectional view of the structure in the same position as shown in Figure 1, taken as indicated at the section line of Figure 5; Figure 3, a section similar to Figure 2 showing the seat structure tilted upwardly to make the latch accessible from the front of the structure; Figure 4, a sectional view similar to Figure 2 showing the structure with the back section and seat section in horizontal position to form a bed; Figure 5, a fragmentary plan view of the structure opened to form a bed; and Figure 6, a fragmentary sectional view showing a modified form of latch.

In the embodiments illustrated, a supporting base frame is in the form of a box having end panels 7, a back panel 8, and a front panel 9. A bottom wall 10 with the side panels, forms a container which may serve to hold pillows, and other bed clothing, if desired. Suitable legs 10a and arm rests 11, shown in dotted lines, may be provided, if desired.

A back section 12 is movably mounted on the end panel 7 in the base frame by means of a pair of rear pitmans 13 and shorter front pitmans 14.

The rear pitmans 13 are connected in the supporting base frame, as indicated at 15, and to the seat section, as indicated at 16. The shorter pitmans 14 are pivoted to the base frame, as indicated at 17, and to the seat frame, as indicated at 18. It will be understood that the linkage arrangement is the same at each end of the supporting frame.

A seat section 19 has an extension 20 which is hinged to the back section 12 at the pivot 18. When the sections are turned to the position illustrated in Figures 4 and 5, it will be seen that their connected central portions are supported by the pitmans 13 and 14 and as the free end of the back portion 12 rests on the top of the panel 8, it is rigidly held in position. The seat section 19, hinged to the back section at 18 and having its free end resting on the top of the front panel 9, is also firmly positioned so that a convertible bed may be formed thereon. It will be understood that each of the sections is formed to receive a suitable upholstered cushion which will also serve as a mattress when the device is transformed into a bed.

In the form shown in Figures 1—5, inclusive, pawls 21 are pivotally mounted at 22 in brackets 23 secured to the back section 12. The pawls are connected for simultaneous operation by means of a cross bar 24 which extends from one end of the structure to the other. A small tension spring 25 is shown extending from the cross bar 24 to the back section 12 and yieldingly urges the pawls upwardly into engagement with lugs 26 provided on the rear end of the seat section 19. While a spring is preferred for this purpose, it will be understood that the pawls may be weighted or other yielding means substituted to produce the same effect.

When the structure is extended to form a bed, as illustrated in Figure 4, it will be understood that it is merely necessary to raise either of the sections 12 or 19 to proper angular relation with the companion section to form a sofa. The two sections and the latch are thus brought to the position shown in Figures 1 and 2 and the structure is ready for use as a sofa. In this position the inner end portion of the seat frame is restrained against further backward movement by means of a stop 7a.

To transform the structure from a sofa to a bed, the two sections and latch are turned as a unit to the position shown in Figure 3 which makes the latch 24 easily accessible from the front of the structure. By depressing the latch,

the seat frame may be lowered into the position shown in Figure 4.

In the form of my invention shown in Fig. 6, the supporting structure, seat section, and back section are constructed the same as described above and accordingly the same reference numbers apply. However, in this form a modified form of latch is illustrated. An arm 27 is pivotally mounted at 28 on an extension 29 of the back section. The arm is provided with a notch 30 to engage a short stud 31 carried by a yoke 32 which is rigidly secured to the back section 19. If desired, arms 27 may be provided at each end of the structure and may be connected by a cross bar 33 which is accessible to release the latch when the structure is turned up to the position illustrated in Figure 6.

The foregoing detailed description has been given for clearness of understanding only, and no unnecessary limitations should be understood therefrom for some modifications will be obvious to those skilled in the art.

I claim:

1. A sofa bed, comprising: a supporting base frame having elevated front and rear panels; a back section linked to said base frame by means of a pair of spaced pitmans at each end of the

base frame, the rear pitmans being longer than the front pitmans; a seat section hinged to said back section so that it may form a horizontal extension thereof when the back section is swung 5 down to form a bed wherein the central connected portions of the sections are supported by the pitmans and the free portions rest on the elevated panels of the supporting base frame and when forming a sofa said seat section having its rear 10 end portion resting on the end panels of the base frame and the front end portions resting on the front panel so as to incline the seat upwardly at the front; and a releasable latch on the sections for holding them in the angular relation 15 required for sitting position, said sections and latch being movable as a unit which may be swung forwardly to expose the latch for release from the front of the structure.

2. A sofa bed as specified in claim 1, in which 20 the latch has pawls pivoted at opposite ends of one of the sections to engage automatically lugs on the companion section when either section is moved from horizontal position to proper angular relation to form a sofa, said pawls being connected for simultaneous operation by means of 25 a cross bar.

MARTIN FOX.
